(57) **ABSTRACT**

A method for manufacturing a luminescent hand for a horological movement, preferably for a watch. The method includes providing a support comprising a light guide and structuring an emergent surface of the light guide so as to extract a maximum amount of light from the luminescent hand. The luminescent hand includes, over a lower face, a layer of luminescent material including one or more deposit(s) of fluorescent material, opposite a light source. The light source is located at locations close to the axis of rotation or away from the axis of rotation but at a distance from the luminescent material. Thus, the light source is not placed on the luminescent hand.

METHOD FOR MANUFACTURING
LUMINESCENT HANDSCROSS REFERENCE TO RELATED
APPLICATIONS

This application is a National Stage of International Application No. PCT/EP2021/074292 filed Sep. 2, 2021, claiming priority based on European Patent Application No. 20213515.8 filed Dec. 11, 2020.

TECHNICAL FIELD

The present invention relates to the field of luminescent hands and more particularly to the manufacture of luminescent hands.

TECHNOLOGICAL BACKGROUND

There are several methods for making hands for horological movements.

Nonetheless, these methods are not suitable for the manufacture of luminescent hands because too often it turns out that the hands return only a small amount of light or concentrate a large part of the light at one point, which is not necessarily the effect pursued by the Applicant.

Indeed, some manufacturing methods lead to the light being extracted only in one plane of the hand or reflected inwards, and therefore, it results in a low luminosity of the hand.

SUMMARY OF THE INVENTION

The present invention aims to solve all or part of the aforementioned drawbacks thanks to a method for manufacturing at least one luminescent hand for a horological movement, preferably for a watch; said manufacturing method comprising at least one:

Providing at least one support; said at least one support comprising at least one light guide; said at least one light guide comprising at least one emergent surface and being configured to guide light; and,

Structuring said at least one emergent surface.

Thanks to this arrangement, it is possible to manufacture a luminescent hand for a horological movement with a light distribution.

According to one embodiment, said at least one structuring is carried out by abrasion, by ablation, by sandblasting, by stamping and/or photo-structuring.

Thanks to this arrangement, it is possible to distribute the light by increasing said at least one emergent surface.

According to one embodiment, said at least one provision of at least one support comprises a deposition of at least one layer of a first optical material; said at least one layer of a first optical material comprising a first refractive index.

According to one embodiment, said deposition of said at least one layer of a first optical material comprises a heat treatment step.

Thanks to either one of these previous arrangements, it is possible to manufacture a luminescent hand with a reflective layer.

According to one embodiment, said at least one provision of at least one support comprises at least one deposition of at least one layer of luminescent material.

Thanks to this arrangement, it is possible to manufacture a luminescent hand.

2

According to one embodiment, said at least one provision of at least one support comprises a deposition of at least one layer of a second optical material; said at least one layer of a second optical material comprising a second refractive index.

According to one embodiment, said first refractive index is lower than said second refractive index.

Thanks to this arrangement, it is possible to refract the light towards said at least one emergent surface.

10 The present invention aims to solve all or part of the aforementioned drawbacks by means of at least one luminescent hand comprising at least one:

Support; said at least one support being configured to form a hand; and

15 Light guide; said at least one light guide comprising at least one emergent surface configured to be rough so as to extract light from said at least one light guide.

Thanks to this arrangement, it is possible to have at least one luminescent hand able to extract a maximum of light 20 from said at least one emergent surface.

According to one embodiment, said at least one light guide comprises at least one layer of a first optical material comprising a first refractive index and at least one layer of a second optical material comprising a second refractive index; said first refractive index is lower than said second refractive index.

Thanks to this arrangement, it is possible to guide the light towards said at least one emergent surface.

BRIEF DESCRIPTION OF THE FIGURES

The invention will be described in more detail hereafter using the accompanying drawings, given by way of examples that are in no way limiting, wherein:

FIG. 1 shows a deposition 520 of at least one layer of a first optical material 120 after provision 510 of at least one support 110 according to one embodiment;

FIG. 2 illustrates a heat treatment step 525 according to one embodiment;

FIG. 3 shows the deposition 530 of at least one layer of luminescent material 130 according to one embodiment;

FIGS. 4 and 5 show the deposition 540 and the formation 550 of at least one layer of a second optical material 140 according to one embodiment;

FIG. 6 represents a step 560 of structuring said at least one emergent surface 190 according to one embodiment;

FIG. 7 shows the cut-out 570 of at least one luminescent hand 100; and,

FIG. 8 illustrates said at least one luminescent hand 100 50 in operation according to one embodiment.

DETAILED DESCRIPTION OF THE
INVENTION

55 There are several types of luminescent hands on the market. Nonetheless, the Applicant proposes a new generation of luminescent hands.

Indeed, the Applicant proposes at least one luminescent hand 100, observable in FIG. 8, comprising at least one support 110 configured to form a hand and at least one light guide 150 comprising at least one emergent surface 190 configured to be rough so as to extract light 910 from said at least one light guide 150.

Said at least one luminescent hand 100, intended to be used in a horological movement, preferably for a watch, may be obtained thanks to the manufacturing method 500 of the Applicant. For this purpose, said manufacturing method

comprises at least one provision **510** of at least one support **110**, preferably a sheet metal **110**, as illustrated in FIG. 1.

Said at least one support **110** receives, during a deposition **520**, at least one layer of a first optical material **120**, preferably at least one optical insulation layer allowing preventing light from being absorbed by said sheet metal **110**, comprising a first refractive index followed by a heat treatment **525** at a determined temperature **521**. Before said deposition **520** of said at least one layer of a first optical material **120**, said sheet metal **110** or said at least one support **110** may be washed or washed and then a plasma treatment may be applied to promote the adhesion of said at least one layer of a first optical material **120**. In this case, said at least one layer of a first optical material **120** may be a resin commercialised by the company POLYRISETM for example, and is intended to optically isolate the surface of said at least one support **110** so that it could absorb as little light as possible. This optical isolation can be permitted thanks to said first refractive index which cannot be greater than 1.60, in particular 1.45 and preferably 1.35.

Said at least one layer of a first optical material **120** may be deposited for example by printing or by spraying, since spraying allows selectively depositing said at least one layer of a first optical material **120** over the useful portions and avoiding wastages.

As mentioned before, said at least one layer of a first optical material **120** undergoes said heat treatment **525** for example for one hour at 300° C. under dinitrogen, so that the solvent of said at least one layer of a first optical material **120** could evaporate, which could be observed in FIG. 2.

As illustrated in FIG. 3, at least one deposition **530** of at least one layer of luminescent material **130** may be carried out on said at least one support **110**, preferably over said at least one layer of a first optical material **120**. Said at least one layer of luminescent material **130**, preferably comprising fluorescent pigments and an adhesive enabling attachment by polymerisation, is intended to illuminate said at least one luminescent hand **100** when said at least one layer of luminescent material **130** is illuminated by a light source having a wavelength range less than 530 nm for example.

Indeed, the fluorescent pigments may be a source of a secondary fluorescent light. In watches, the fluorescent pigments can be excited remotely by a source of blue or ultraviolet light for example. It should be noted that other techniques such as screen-printing or digital printing could be used for said at least one deposition **530** of said at least one layer of luminescent material **130**.

A UV plasma treatment lasting a few minutes follows in order to promote the adhesion of at least one layer of a second optical material **140**, of the ORMOCLEAR®10 resin type from MICRORESIST TECHNOLOGY™ for example, which takes place by rod coating or doctor blade type deposition **540**, which could be translated as spread coating as represented in FIG. 4 for example.

Still with reference to FIG. 4, one could observe that said at least one layer of a second optical material **140** can be pushed by a blade so as to fill the different cavities that might exist.

It should be noted that said at least one layer of a second optical material **140** comprises a second refractive index greater than said first refractive index so as to guide the fluorescent light emitted by said at least one layer of luminescent material **130**.

Visible in FIG. 5, said at least one layer of a second optical material **140** may be fixed by exposure under ultraviolet light **552** and under vacuum **551**. Alternatively, it may be

possible to laminate a plastic film in order to expel air before insulation under ultraviolet light.

Indeed, the lower face of said at least one layer of a second optical material **140** comprises one or more deposit(s) of fluorescent material, opposite a light source **900**, so as to establish optical contact with said at least one layer of luminescent material **130**, and as mentioned before, at least one layer of luminescent material **130** may be formed of fluorescent pigments incorporated in a glue. Alternatively, the fluorescent material may be embedded in the light guide layer.

In operation, the light source **900** illuminates said at least one layer of luminescent material **130** having a wavelength shorter than the wavelength that will be emitted again by said at least one layer of luminescent material **130**. Said at least one layer of luminescent material **130** absorbs this incident light and emits it again **910**, in particular in said at least one layer of a second optical material **140**. The presence of said at least one layer of a first optical material **120** enables a total internal reflection of the fluorescent light propagating in said at least one layer of a second optical material **140** and thus avoids a progressive absorption in said at least one support **110**.

The difference in refractive index between said at least one support **110** and said at least one layer of a second optical material **140** is comprised within the interval ranging from 0.5 to 0.9, preferably from 0.55 to 0.8, more preferably from 0.6 to 0.75, allows increasing the value of the critical angle and therefore the numerical aperture of said at least one layer of a second optical material **140** in order to maximise the coupling of the fluorescent light. It should be noted that the presence of said at least one layer of a first optical material **120** enables the transmission without loss in said at least one layer of a second optical material **140** once the light has been coupled and that the index of said at least one layer of a first optical material **120** influences the amount of coupled light. Said at least one layer of a first optical material **120** may have a thickness comprised within the interval ranging from 2 µm to 15 µm, preferably from 3 µm to 12 µm, still more preferably from 5 µm to 10 µm. A multitude of total internal reflections in said at least one layer of a second optical material **140** follow until reaching one end of said at least one luminescent hand **100** where the light flux is transmitted outwards.

Finally, a step **560** of structuring said at least one emergent surface **190**, schematised in FIG. 6, may be carried out by abrasion **565**, by ablation **565**, by sandblasting **565**, by stamping **565** and/or photo-structuring **565** in order to increase said at least one emergent surface **190** and/or totally or partially avoiding light **910** being refracted again which would lead to a concentration of a large part of the light at one point for example. Indeed, a surface structuring may be provided for, i.e. the material of said at least one layer of a second optical material **140** may be peeled locally so as to induce a roughness, over said at least one emergent surface **190** of said at least one layer of a second optical material **140** so that extraction of the light **910** is facilitated therefrom.

In addition, a light diffusion area, which can be made by deposition of a resin, may be added to said at least one luminescent hand **100**, extending beyond, i.e. projecting from said at least one support **110** to facilitate the leakage of the luminous flux and to obtain a decorative pattern on said tip. According to embodiments that are not represented, not only the tip of said at least one luminescent hand **100** but also the edges of said at least one luminescent hand **100** and possibly the head comprise said at least one emergent surface **190**.

5

A step 570 of cutting said at least one luminescent hand 100 is carried out for example by laser 571, preferably, because the laser 571 can melt said at least one light guide 150, composed of said at least one layer of a first optical material 120 and at least one layer of a second optical material 140, and produce a polished surface condition, FIG. 7, which allows reflecting a light 910 towards the inside of said at least one light guide 150.

In the example of FIG. 8, said at least one emergent surface 190 corresponds to a peripheral surface of said at least one luminescent hand 100 in order to illuminate the profile of said at least one luminescent hand 100. Indeed, when said at least one layer of luminescent material 130 is subjected to said light source 900 having a wavelength comprised between 330 nm and 560 nm, said at least one layer of luminescent material 130 generates said light 910 which is extracted via said at least one emergent surface 190 of said at least one light guide 150. Of course, it is also possible to place the light sources LEDs at appropriate locations for the considered product, like for example close to the axis of rotation or away from the axis of rotation and to add an optical coupler allowing bringing the luminous flux of said light source 900 to the appropriate place to excite the fluorescent material of said at least one luminescent hand 100. Thus, unlike the prior art, said light source 900 is not placed on said at least one luminescent hand 100.

The invention claimed is:

1. A method for manufacturing at least one luminescent hand for a horological movement, the manufacturing method comprising:

providing at least one support supporting the luminescent hand; and

forming on the at least one support a light guide comprising at least one emergent surface and being configured to guide a light, the forming step including the following sub-steps:

depositing on said support at least one layer of a first optical material comprising a first refractive index and allowing preventing the light from being absorbed by the support;

5

6

depositing at least one layer of luminescent material over the at least one layer of the first optical material; depositing of at least one layer of a second optical material, said at least one layer of a second optical material comprising a second refractive index; and, structuring said at least one emergent surface so that this emergent surface is rough so as to extract the light from said at least one light guide.

2. The manufacturing method according to claim 1, wherein said at least one structuring is carried out by abrasion, by ablation, by sandblasting, by stamping and/or photo-structuring.

3. The manufacturing method according to claim 1, wherein said deposition of said at least one layer of a first optical material comprises a heat treatment step.

4. The manufacturing method according to claim 1, wherein said at least one deposition of at least one layer of luminescent material comprises fluorescent pigments.

5. The manufacturing method according to claim 1, wherein said first refractive index is lower than said second refractive index.

6. A luminescent hand for a horological movement comprising:

a support supporting the hand; and
a light guide, said at least one light guide comprising at least:

a layer of a first optical material comprising a first refractive index and allowing preventing light from being absorbed by the support;

a layer of luminescent material over the at least one layer of the first optical material;

a layer of a second optical material comprising a second refractive index; and

an emergent surface configured to be rough so as to extract light from said at least one light guide.

7. The luminescent hand according to claim 6, wherein said first refractive index is lower than said second refractive index.
